UNITED STATES PATENT OFFICE

HARRY G. WEDLER, OF ST. LOUIS, MISSOURI, ASSIGNOR TO THE WEDLER-SHUFORD CO., OF ST. LOUIS, MISSOURI, A CORPORATION OF MISSOURI

COVER FOR SEAT BACKS AND THE LIKE

Application filed June 22, 1928. Serial No. 287,447.

This invention relates to covers adapted to be applied to the back rests of seats, or to cushions and the like.

An object of the invention is to provide an improved cover adapted to be applied to the back rests of seats, or to cushions and the like, and comprising front and rear sections adapted to cover the front and rear surfaces of the back rest of a seat, or the upper and lower surfaces of cushions, and connected by an elastic side portion whereby the device may be applied to back rests and cushions of different thickness and yet fit snugly thereon.

Another object of the invention is to provide an improved cover in the form of a slip adapted to be slipped over the back rest of a seat, or over a cushion, to enclose the same, said cover being of approximately box-like form and having a substantially non-elastic front or top, and an elastic side connecting the front or top with the rear or bottom side of the slip, so as to permit application of the device to back rests, or cushions, of different sizes.

Another object of the invention is to provide a device of the character mentioned including a flap in connection with the edge of one of the members adapted to be folded around an edge of the back rest of the seat, or of the cushion, so as to enclose the same and cooperate with the remaining structure to hold the device in proper adjustment.

Other objects will appear from the following description, reference being made to the accompanying drawing in which

Fig. 1 is a perspective view of a seat having my improved cover applied to the back rest thereof.

Fig. 2 is a side elevation of the seat showing the cover on the back rest.

Fig. 3 is a rear elevation of the device detached from the seat.

Fig. 4 is a sectional view of the upper end of the cover.

Fig. 5 is a sectional view showing the attachment of the flap to the lower end of the front or top of the cover.

In the embodiment of my improved cover shown in the accompanying drawing the

front or top comprises a section, preferably of non-elastic material. This section should be a reticulated textile, though I do not restrict myself to such material. Straw matting is suitable for this purpose, as it possesses the desirable qualities of flexibility and pliability so as to conform to the contour of the surface of the back rest or cushion to which it is applied and yet is sufficiently non-elastic and stiff so that it will not readily fold or crumple upon itself, but will maintain an attractive appearance longer than many other materials. The warp straws or threads 1 extend vertically, or from front to rear, while the woof threads 2 extend transversely and may be arranged in pairs, as shown. A non-elastic lining 3 of textile or other suitable material is applied to the inner side of the front or top of the cover. The rear or underside of the cover comprises a section 4 of non-elastic material which may be of the same type of straw matting as that included in the front or top section. As shown, the rear or bottom panel is of smaller area than the front or top, though the construction may be varied in this respect.

The sides of the cover or slip comprise an elastic textile strip 5 extending from adjacent lower corners of the front and rear panels upwardly along adjacent vertical side edges, and thence transversely along the top edges and downwardly along the opposite vertical edges to the opposite lower corners of the panels, leaving the lower or front end of the box-like structure open so that the device may be readily slipped upon a back rest of a seat, or upon a cushion. The edges 6 of the strip 5 extend outwardly against the marginal portions of the lining 3 and the back panel 4, respectively. And, the margins of the front and rear panels including for the front panel the margins of the surface section, the lining 3 and the strip 5, and including for the back or bottom the margins of the panel 4 and the strip 5, are enfolded within a binding strip 7 secured to the other elements by lines of stitching 8. The binding strip 7 continues across the lower or front edges of the front and rear portions of the

cover, as do the lines of stitching 8 to secure the parts together.

The front or open lower end of the cover is equipped with a flap 9, an edge of which is enfolded between the margin of the lining 3 and the binding strip 7, a line of stitching 8 securing the parts together. The margin 10 of the flap 8 is folded upon itself at the rear under side thereof and along all exposed edges thereof and secured in this position by a row of stitches 11.

A cover of this character may be easily applied and easily removed. It is readily applicable to back rests or cushions of different sizes because the flexible and elastic strip 5 is expansible for this purpose. The cover may be slipped upon a back rest or cushion, the open side or end of the cover permitting such application. After the cover is applied the flap is folded around the side or end of the back rest or cushion and in the embodiment shown is tucked between the rear or lower panel 4 and the back rest or cushion and cooperates with the remaining cover structure to hold the device in position. The cover possesses many advantages made apparent from the foregoing description and obtains all of its intended objects and purposes very efficiently and satisfactorily. A wide range of materials may be used and the construction and arrangement of the parts may be varied without departure from the nature and principle of the invention.

Accordingly, I do not restrict myself unessentially in these or other particulars, but what I claim and desire to secure by Letters Patent is:—

1. A cover of the character described comprising opposite panels for covering opposite sides of a seat cushion or back, and an elastic strip connecting said panels along all edges other than one edge and permitting spacing of said panels and forming therewith a box-like structure which is open at said one edge of said panels to receive the seat back or cushion.

2. A cover for a seat back or cushion comprising a panel of non-elastic material, a lining secured against the inner side of said panel, a cooperating non-elastic panel, and an elastic strip connecting said panels along their marginal portions and forming therewith a box-like structure adapted to receive the back rest of a seat or cushion.

3. A cover for the back rest of a seat or a cushion comprising two non-elastic panels for covering the opposite sides of the back rest or cushion, and an elastic strip connecting the marginal edges of said panels and arranged to cover the side edges of a back rest of a seat or cushion.

4. A cover for a seat back or cushion comprising a panel of non-elastic material, a lining covering the inner side of said panel,

a cooperating non-elastic panel, an elastic strip having its marginal edges lapping the marginal edges of said second panel and said lining, means attaching the marginal edges of said strip to said panels and to said lining in a relationship to form a box-like structure adapted to receive the back rest of a seat or cushion, and a flap extending nearly the width of said cover and having one edge attached to said lining and said non-elastic material to which said lining is secured and being of a length greater than the width of said strip whereby the free edge of said flap may be tucked between the free edge of the opposite panel and the adjacent portion of the seat back or cushion.
